CARTRIDGE CASE VENTING MACHINE

Edward Moyer, Trenton, N. J.

Application July 10, 1946, Serial No. 682,524

16 Claims. (Cl. 164—87)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to a machine for punching a vent hole in each of a succession of cartridge cases or like metal objects.

It is an object of this invention to provide a vent-hole-punching machine which is substantially automatic in its operation and which is provided with devices which prevent the feeding of cartridge cases to the machine or disconnect the power from the machine in the event of an interruption to the proper functioning of the machine.

A more specific object of this invention is to provide a cartridge case venting-machine having a cam controlling the feed of cartridge cases to the machine and having a spring-pressed latch or detent normally holding the cam in its operative position but yieldable upon maloperation of the machine to allow the cam to move to inoperative position and having a stop for restoring the cam to operating position.

Another specific object of the invention is to provide a machine for punching vent holes in cartridge cases or similar metal pieces, said machine having a clutch controlling the application of power to the machine, a plunger movable into and out of the path of travel of cartridge cases through the machine and adapted to move a cartridge case (which is passing through the machine in reversed end-for-end position) sufficiently to operate a clutch-disengaging mechanism and, thereby, to shut off power from the machine.

A further particular object of this invention is to furnish a relatively reciprocating punch and a die into which the end of the punch enters after it has pierced a hole in the head of a cartridge case or like work pieces and a punch-guide slidably mounted on the punch and adapted to enter the primer-receiving cavity in the head of the cartridge case so as to guide the punch while it forms a vent hole in the head of the cartridge case.

Yet another object of this invention which is worthy of mention is the furnishing of a no-vent detecting stem slideable so as to enter the newly-formed vent hole or to engage the non-vented head of a cartridge case and to be moved by the cartridge case so that the stem operates a de-clutching-linkage and shuts off power from the machine.

Other and further objects of this invention will be readily apparent to those skilled in the art to

2

which it pertains or will be manifest as the description of the invention (herein given) proceeds.

For further exposition of this invention, reference may be had to the annexed drawings and specification, at the end whereof, the novel features desired to be protected by Letters Patent are specifically pointed out and claimed.

In the drawings:

Fig. 1 is a top plan view with some parts broken away in a horizontal cross section.

Fig. 2 is a view in vertical longitudinal cross section on line 2—2 of Fig. 1.

Fig. 3 is a view in vertical longitudinal cross section on line 3—3 of Fig. 1.

Fig. 4 is a view in vertical longitudinal cross section on line 4—4 of Fig. 1 and on a considerably enlarged scale.

Fig. 5 is a view in vertical longitudinal cross section on line 5—5 of Fig. 1 and on an enlarged scale.

Fig. 5A is a view similar to Fig. 5 showing the parts in inoperative position.

Fig. 6 is a view in vertical longitudinal cross section on line 6—6 of Fig. 1 and on an enlarged scale.

Fig. 6A is a view in vertical longitudinal cross section showing the parts illustrated in Fig. 6 but on a further enlarged scale and in engaged position.

Fig. 7 is a view of the whole machine in side elevation with some parts broken away in vertical cross section.

Fig. 8 is a view in vertical transverse cross section on line 8—8 of Fig. 7.

Fig. 9 is a view in vertical transverse cross section on line 9—9 of Fig. 7.

Fig. 10 is a view in vertical transverse cross section on line 10—10 of Fig. 7.

Fig. 11 is a view in vertical transverse cross section on line 11—11 of Fig. 7.

Fig. 12 is a partial end view on line 12—12 of Fig. 7 with parts broken away.

Fig. 13 is a view in vertical transverse cross section on line 13—13 of Fig. 7.

Fig. 14 is a view in vertical transverse cross section on line 14—14 of Fig. 7.

Fig. 15 is a view in vertical transverse cross section on line 15—15 of Fig. 7.

Fig. 16 is a view in vertical transverse cross section on line 16—16 of Fig. 7 and on an enlarged scale.

Fig. 17 is a view in vertical transverse cross section on line 17—17 of Fig. 7. Line 17—17 overlaps line 16—16 at the upper end thereof so

that the upper portion of each of these views is taken on the same plane.

Fig. 18 (on Sheet 2) is a view in horizontal cross section on line 18 of Fig. 7 showing the punch, the punch-guide, and the pins which support the punch guide.

Driving mechanism

Power is applied to the machine by means of a belt B passing over a sheave 20 fastened on the drive shaft 21 which is mounted in bearings in the bed 22 by means of bearing caps 23. A gear 24 on one end of the drive shaft 21 meshes with a gear 25 which forms a part of the driving member 26 of a tooth clutch. The driven member 27 of the tooth clutch has a hand wheel 28 on it which permits manual turning of the crank shaft 29 which is fastened to the driven member 27 of the clutch. Shaft 29 is rotatively mounted in bed 22 by means of bearing caps 30.

Clutch-operating linkage

Figs. 1, 3, 12 and 14 show that bed 22 carries on one side a bracket 31 on which is secured a pivot 32 supporting for rocking movement on it a clutch-operating lever 33 having at one end a handle 34 and at its opposite end a pin 35 by which it is pivotally connected to a link 36 secured by a screw 37 to the driven member 27 of the clutch. Spring 38 stresses lever 33 and the driven member 27 of the clutch towards disengaged or disconnecting position. Handle 34 is operable to engage clutch members 26 and 27. Bed 22 carries a bracket 39 in which is mounted a pin 40 pivotally supporting a latch 41 having at one end a weighted manually operable handle 42 and its other or inner end 43 underlying the flat lower face 44 of one end 45 of a substantially U-shaped bracket 46 which is pivotally mounted on a pin 57 on the punch head (hereinafter described) and which carries a manually operable handle 48.

Connecting rods

Figs. 1, 2, 7 and 9 show that crank shaft 29 has an offset crank pin 49 to which is rotatably secured a die head connecting rod 50 by means of a connecting rod cap 51. The opposite end of die head connecting rod 50 is pivotally connected to a slidably mounted die head (hereinafter described) by means of a pin 52. Crank shaft 29 also has, as parts of it, eccentrics 53 whose peripheries are surrounded by tubular straps 54 to provide rotatable connections for the ends of a pair of punch head connecting rods 55. Punch head connecting rods 55 are pivotally secured at their opposite ends to tubular straps 56 in which are rotatably mounted pins 57 having connection with the punch head (hereinafter described). Nuts 58 have interior faces of reduced diameter which ride in and serve as bushings or pivotal supports for the U-shaped bracket 46.

Feed

Figs. 1, 4, 5, 5A, 6, 6A, 7, 13, 14, 16 and 17 show a mechanism for feeding a supply of cartridge cases C or like work pieces to the machine. Fig. 4 shows that the cartridge cases C are fed in a line end-to-end through a flexible metallic tube 60 whose lower end is received in a rigid pipe 61 forming the top of the magazine or hopper 62 which is mounted on the bed 22 and is relatively stationary thereon. Figs. 16 and 17 show that magazine 62 carries a pin 63 on which is pivotally mounted a U-shaped bracket 64 which is stressed by a spring 65 so that the ends 66 of the U-shaped

bracket 64 tend to move upward about pin 63 as a pivot. At its base 67 or opposite end from the ends 66, U-shaped bracket 64 carries a pin 68 having an enlarged head 69 which abuts a washer 70 which overlies and slides on a flat face 71 forming the mouth of an opening 72 in an L-shaped striker 73 pivotally mounted on U-shaped bracket 64 by means of a pivot 74. A spring 75 stresses a washer 76 which slides on the flat outer face 77 of the striker 73 and which also overlies one end of the elongated opening 72 passing through the striker 73.

Magazine 62 carries, on its face adjacent to the ends 66 of U-shaped bracket 64, a pair of plates 80 which fit into notches in the vertical edges of a flat body 81 so that the body 81 is mounted for vertically reciprocating movement. Body 81 carries two trunnions 82 on which are mounted rollers 83 riding on the flat upper surfaces of the ends 66 of the U-shaped bracket 64. A screw 84 is screw-threadedly secured to the body 81 and has an intermediate surface 85 of reduced diameter which provides a pivotal bearing for one end of a bell crank lever 86 which is pivotally mounted on a pin 87 screw-threadedly supported from the upper part of magazine 62. The opposite end of crank lever 86 has secured thereto a screw 88 which forms a bushing on which is rotatably mounted cam follower disc 89.

Figs. 5, 5A and 14, particularly, show a cam 90 which is slidably mounted on the die head (to be described later) by means of a slide 91 riding in slideways 92. Cam 90 has in its lower surface a hemispherical depression 93 which normally receives a portion of ball 94 which is stressed by a spring 95 so as to form a yielding latch or detent which normally holds the cam 90 against sliding movement relative to the die head. A stop 99 mounted on magazine 62 in the path of travel of the cam 90 end serves to engage and reset the cam 90 in operative position after it has been moved to inoperative position.

Centering device

Figs. 6 and 16 show that the lower portion of the walls of the magazine 62 is provided with means for centering or accurately locating each cartridge case C in succession during the vent-hole-punching operation, the detecting operation which insures that a vent-hole has been punched, and the ejecting operation. These centering devices are very simply formed of six pairs of confronting balls 100 and 101 (only one pair being shown in Fig. 16) which protrude from the inner walls of the magazine 62 and which are respectfully stressed by springs 102 and 103 into engagement with the sides of each cartridge case C as it passes in succession through the magazine.

Punch head

Figs. 1, 6, 6A, 7, 8, 9, 10 and 12 show the punch head generally indicated at 110 and slidably mounted in slideways 111 forming part of bed 22 by means of a slide 112. Figs. 6, 6A and 18 show a punch 113 which is mounted in the punch head 110 by means of a screw 114. Projecting end 115 of the punch head is of reduced diameter and has slidably mounted thereon a punch-guide 116 which has a projecting portion 117 of reduced diameter and arranged to enter a primer cavity PC in a cartridge case C and to thus center the end 115 of the punch during the vent-hole-punching operation. (The primer cavity PC is not formed by the inventive machine herein described, but instead is formed in the case C prior

to entering the instant machine.) The punch-guide 116 also acts as a stripper during the retracting of the punch tip 115 since the punch-guide 116 presses against the head of the cartridge case C and allows the punch tip 115 to be withdrawn from the vent-hole which it has just formed in the cartridge case C. The punch-guide 116 is mounted on a plate 118. Figs. 7 and 18 show pins 119 which slidably support plate 118 and punch-guide 116 which is stressed by springs 120 so that the punch-guide yieldingly engages the cartridge case head.

Die head

Figs. 1, 5, 5A, 6, 6A, 7, 14, 15 and 18 show the die head (generally indicated at 121) slidably mounted in slideways 122, which form part of bed 22, by means of a slide 123. Figs. 6 and 6A show the die 124 mounted in the die head 121 and having an end 125 pierced by a perforation 126 which receives the tip 115 of the punch in it when the punch has completed the vent-hole-forming operation. Fig. 6A shows the punch tip 115 entering the perforation 126 in the die 125. A conduit 129 communicates with the inner end of the perforation 126 and ends in an opening in the bottom of the die 124. Conduit 129 serves to remove the plug or piece of metal which has been cut away so as to leave the vent hole in the cartridge case. The die head also has an ejector 127 fastened to it and arranged to enter the open end of the lowest cartridge case C in the magazine 62 and thus to eject that cartridge case from the magazine through a hole 128 in the punch head 110. A screw 130 engages with the die head 121 and holds a clamp 131 which abuts at its outer end upon an insert 132 which bears at its lower end upon the inner end of the die 124 and thus secures the die firmly in position in the die head 121.

Position tester

Figs. 1, 5, 5A, 6, 6A, 7, 8, 9, 10 and 11 show that die head 121 has mounted on insert 132, which forms a part of it, a finger 140 which is secured to the insert 132 by means of a set screw 141. On punch head 110, opposite finger 140, is a screw tip 142 of frustro-conical shape. Screw tip 142 is supported in a C-shaped clamp 143. (See Fig. 11.) Tightening screw 144 secures C-shaped clamp 143 against screw tip 142 and against a plunger 145 which is slidable through a clamp 146 secured to punch head 110 as by a clamping stud 147. At its rear end plunger 145 is secured to an L-shaped latch 148 by means of a set screw 149 (Fig. 8). As is best seen in Figs. 1 and 6, L-shaped latch 148 engages with a cam 150 having a sloping face 151 which abuts the face of U-shaped bracket 46.

Vent-hole tester

Figs. 1, 6, 6A, 7, 8, 9, 10 and 12 disclose plunger 160 having a conical head 161 arranged for movement with the punch head so that the conical head 161 enters the vent-hole in the cartridge case C immediately after the vent-hole has been formed. Figs. 6 and 8 show that the outer end of plunger 160 is secured to cam 150 by means of a set screw 162 so that the cam 150 can be operated either from the lever screw tip 142 or by means of plunger 160.

Operation

The operation of this device is believed to be readily understood from the foregoing descrip-

tion but a short statement of the mode of operation of this machine is as follows:

Cartridge cases C which are to have a vent-hole punched in the head thereof are fed (head foremost) through the flexible metallic tube 60 so that they enter the magazine or hopper generally indicated at 62. If the belt B is turning the drive sheave 20 and the drive shaft 21 while the clutch 26-27 is engaged, the crank shaft 10 29 is rotated and the punch head 110 and the die head 121 are reciprocating alternately toward and away from each other and the magazine or hopper 62. As the cam 90 moves to the right as seen in Fig. 7, cam follower 89 is raised about pivot 87 in the direction of the arrow A. This lowers body 81 so that discs 83 roll on the ends of 66 of the U-shaped bracket 64 and cause it to turn about its pivot 63 whereby the striker 73 rises from the position in which it is shown in Fig. 17 into the position in which it is shown in Fig. 18. This movement of the striker 73 pushes upon one of cartridge cases C so that it falls on top of a pile or stack of such cases contained in the magazine or hopper 62. Movement of die head 121 and consequently of cam 90 toward the left, as seen in Fig. 7, allows the stress of spring 65 to turn U-shaped bracket 64 about its pivot 63 so that the ends 66 of the bracket 64 rise carrying with them discs 83 and consequently body 81, and thus turning crank lever 86 about its pivot 87 so that cam follower 89 rides on the lower face of cam 90. The next stroke of cam 90 to the right, as seen in Fig. 7, again causes the same sequence of operations and lowers body 81 so that the cavity 98 in the inner wall of the body engages the top of the uppermost cartridge case C and depresses the whole stack of cartridge cases in the magazine 62. The bottom cartridge case C has been ejected to permit this movement. If any obstruction occurs in the feed of cartridge cases so that the body 81 cannot be lowered, the cam 90 strikes the cam follower 89, which is still in lower position, with such force that the latch or detent 94 is depressed against the stress of its spring 95 and disengages itself from the depression 93 thereby allowing cam 90 to remain behind as the die head 121 moves to the right. Cam 90 therefore is in the inoperative position in which it is shown in Figure 5A. The subsequent left-hand movement of die head 121 carries cam 90 with it so that the cam 90 strikes against the stop 99 (Fig. 7). This engagement of cam 90 with stop 99 resets the cam into its operative position in which it is shown in Fig. 5.

Figs. 4, 6 and 6A show that the head of each of the cartridge cases C must be nearest the punch head 110 so that the punch tip 115 can pierce the cartridge case head. If a cartridge case is fed to the magazine with its head nearest the die head 121, that is to say with its ends reversed from the desired position, finger 140 engages with the head of the cartridge case and causes the open end of the cartridge case to slide out of the magazine 62 and to engage the screw tip 142 and move it to the left as seen in these drawings. This movement of screw tip 142 moves the C-clamp 143, the slideable rod 145, the L-shaped latch 148 and the cam 150, so that the cam face 151 slides under the base of the U-shaped bracket 46. This sliding movement cams the U-shaped bracket 46 upward about its pivots 58. The end 45 of the U-shaped bracket 46 is thus caused to lower. This raises the 75 weighted handle 42 of the pivoted latch 41 about

its pivot 40. Fig. 12 shows the fit of handle 34 into a notch in pivoted latch 41. Lifting the weighted handle 42 frees the handle 34 of the clutch-operating lever 33. Spring 38 then turns the clutch-operating lever 33 about its pivot 32 so that the driven member 27 is disengaged from the driving member 26 of the clutch. This shuts off the power from the crank shaft 29 and consequently stops the machine.

When the machine is operating properly, the rotary movement of the crank shaft 29 causes movement of the die head 121 through the die head connecting rod 50 and movement of the punch head 110 through the punch head connecting rods 55. The projection 117 on the punch-guide 116 enters the primer-receiving cavity PC so that the punch-guide centers the punch tip 115 in order that it may punch a vent-hole directly in the center of the cartridge case head. At the same time, the die 124 has entered the open end of the cartridge case and traveled the length of the cartridge case so that it contacts with the inner face of the head of the cartridge case C and supports it during the punching operation. The cut-off plug or piece of metal (which has been removed to form the vent-hole) passes through the perforation 126 in the die 124 and escapes from the machine through the conduit 129.

The spring pressed balls 100 and 101 cooperate by pressing on the opposite sides of a cartridge case so as to center it during this punching operation.

The next movement of the punch head 110 and the die head 121 towards each other and into the interior of the magazine 62 causes the rod 160 to move so that its conical tip 161 enters the vent-hole which has been pierced in the head of the cartridge case C on the preceding stroke. If no vent-hole has been formed, or if the vent-hole is of improper size, or in the wrong place, the rod 160 is moved to the left, as shown in the drawings, carrying with it the cam 150. This causes the cam face 151 to lift the rear or bottom portion of U-shaped bracket 46 and thus release latch 41 so that spring 38 operates the clutch actuating lever 33, disengages clutch 26—27, and cuts off power from the crank shaft 29.

The next following movement of punch head 110 and die head 121 toward each other causes the ejector 127 to enter the open end of the lower-most cartridge case C and press upon the inside of the head and thereby expel the cartridge case through the hole 128 provided for its reception in the punch head 110.

It will be readily understood that many mechanical variations of this machine are possible within the scope of this invention and that no limitation is to be implied from this description, save as the scope of the appended claims may require.

I claim:

1. A machine for punching a vent in a cartridge case or the like, including, a drive shaft, a crank shaft, a clutch connecting or disconnecting said drive shaft and said crank shaft, a relatively stationary hollow magazine into which the cartridge cases to be punched are fed and in which the cartridge cases are held during the operation of the machine, a feed mechanism furnishing a supply of cartridge cases to said magazine, a cam and a cooperating cam-follower forming part of the operating connection between said feed mechanism and said drive shaft, a

spring-pressed latch customarily holding said cam in its normal operating position and yielding to permit said cam to move to inoperative position upon an obstruction of the feed to said magazine, a stop in the path of travel of said cam which resets said cam to its normal operating position, a plurality of spring-pressed balls mounted in the wall of said magazine so as to engage each of said cartridge cases in succession to hold it in position while it is worked on by the machine, a plunger driven by said crank shaft into and out of said magazine so as normally to enter the open end of a cartridge case or to engage the head end of a cartridge case and push a portion of the cartridge case out of the machine if the cartridge case has entered the magazine in reversed position, a clutch-operating linkage having a part positioned so as to be engaged by the protruding portion of the cartridge case and to be operated thereby to release said clutch, a punch connected to said crank shaft and mounted for sliding movement relative to said magazine, a punch centering device slidably mounted and movable into the primer-cavity in a cartridge case so as to guide the punch while punching a vent in the cartridge case, a die connected to said crank shaft and mounted for sliding movement relative to said magazine so as to enter the open end of a cartridge case and to receive the end of the punch in the die.

2. A machine for punching a vent in a cartridge case or the like, including, a relatively stationary hollow magazine into which the cartridge cases to be punched are fed and in which the cartridge cases are held during the operation of the machine, a feed mechanism furnishing a supply of cartridge cases to said magazine, a cam-follower operating said feed mechanism, a cam operating said cam-follower, and a spring-pressed latch customarily holding said cam in its normal operating position and yielding to permit said cam to move to inoperative position upon an obstruction of the feed to said magazine.

3. A machine for punching a vent in a cartridge case or the like, including, a relatively stationary hollow magazine into which the cartridge cases to be punched are fed and in which the cartridge cases are held during the operation of the machine, a feed mechanism furnishing a supply of cartridge cases to said magazine, a cam-follower operating said feed mechanism, a cam operating said cam-follower, a spring-pressed latch customarily holding said cam in its normal operating position and yielding to permit said cam to move to inoperative position upon an obstruction of the feed to said magazine, and a stop in the path of travel of said cam which resets said cam to its normal operating position.

4. A machine for punching a vent in a cartridge case or the like, including, a magazine having a passageway through it along which the cartridge cases travel in the operation of the machine, a cooperating punch and die mounted for reciprocating movement towards and away from each other so as to receive in succession the head of each of the cartridge cases between the punch and the die whereby the die supports each cartridge case during the punching operation of the punch, a plurality of balls confronting each other in spaced pairs on opposite walls of said magazine passageway and spaced vertically and horizontally suitable distances to engage a cartridge case between them, and springs stressing said balls towards engagement with a cartridge case and providing yielding movement to permit place-

ment and removal of each of the cartridge cases in succession to and from between said balls and providing sufficient tension so that the balls hold each of the cartridge cases in succession while a vent is punched in the head of the cartridge case.

5. A machine for punching a vent in a cartridge case or the like, including, a drive shaft, a crank shaft, a relatively stationary hollow magazine into which the cartridge cases to be punched are fed and in which the cartridge cases are held during the operation of the machine, a punch connected to said crank shaft and mounted for sliding movement relative to said magazine, and a die connected to said crank shaft and mounted for sliding movement relative to said magazine so as to enter the open end of a cartridge case and to receive the end of the punch in the die after a vent has been punched in a cartridge case.

6. A machine for punching a vent in a cartridge case or the like, including, a drive shaft, a crank shaft, a clutch connecting or disconnecting said drive shaft and said crank shaft, a relatively stationary hollow magazine into which the cartridge cases to be punched are fed and in which the cartridge cases are held during the operation of the machine, a clutch-operating linkage, and a stem driven by said crank shaft into and out of said magazine so as normally to enter a vent punched in a head of a cartridge case or to engage the unvented head of a cartridge case and to be moved thereby to actuate said clutch-operating linkage to release said clutch.

7. A machine for punching a vent in a cartridge case or the like, including, a drive shaft, a crank shaft, a relatively stationary hollow magazine into which the cartridge cases to be punched are fed and in which the cartridge cases are held during the operation of the machine, a punch connected to said crank shaft and mounted for sliding movement relative to said magazine, a die connected to said crank shaft and mounted for sliding movement relative to said magazine so as to enter the open end of a cartridge case and to receive the end of the punch in the die after a vent has been punched in a cartridge case, and a plurality of spring-pressed balls mounted in the wall of said magazine and stressing each of said cartridge cases in succession to hold it in position while it is worked on by the machine.

8. A machine for punching a vent in the end of a cartridge case or the like, including, a drive shaft, a crank shaft, a relatively stationary hollow magazine into which the cartridge cases to be punched are fed and in which the cartridge cases are held during the operation of the machine, a punch connected to said crank shaft and mounted for linear sliding movement relative to said magazine, a die connected to said crank shaft and mounted for linear sliding movement relative to said magazine in a direction opposite to the sliding of the punch so as to enter the open end of a cartridge case and to receive the end of the punch in the die after a vent has been punched in a cartridge case, and an ejector driven by said drive shaft into a punched cartridge case in said magazine and to eject said punched cartridge case from said magazine and from the machine.

9. A cartridge - case - vent - forming punching machine, including, a relatively stationary hollow magazine into which the cartridge cases to be punched are fed and in which the cartridge cases are held during the operation of the machine, a punch mounted for sliding movement so that the tip of the punch enters and leaves the hollow in

said magazine, a die mounted for sliding movement so that the tip of said die enters and leaves the hollow in said magazine and receives the tip of said punch in the tip of said die after the tip of said punch has formed a vent in a cartridge case, power-driven mechanism connected to said punch and to said die thereby giving said sliding motion to said punch and to said die, and a punch-centering device slidably mounted on said punch and movable into the primer-cavity in a cartridge case so as to guide the punch while punching a vent in the cartridge case.

10. A machine for punching primer vent holes in cartridge cases, including, a punch mounted for sliding movement so that the tip of the punch penetrates the blind end of a primer cavity in a stationarily held cartridge case and punches a vent hole therethrough, a die mounted for sliding movement in a direction opposite to the sliding of the punch so that the tip of said die enters and leaves the open end of said cartridge case and receives the tip of said punch in the tip of said die after the tip of said punch has formed the vent in a cartridge case primer cavity, the power-driven mechanism connected to said punch and to said die thereby giving said sliding motions to said punch and to said die, and an ejector driven by said power-driven mechanism so as to engage the punched cartridge case and to eject said punched cartridge case from the machine.

11. A cartridge-case-vent-forming punching machine, including, a relatively stationary hollow magazine into which the cartridge cases to be punched are fed and in which the cartridge cases are held during the operation of the machine, a feed mechanism furnishing a supply of cartridge cases to said magazine, a cam-follower operating said feed mechanism, a cam operating said cam-follower, a spring-pressed latch customarily holding said cam in its normal operating position and yielding to permit said cam to move to inoperative position upon an obstruction of the feed to said magazine, and a power-driven mechanism connected to said cam thereby giving movement to said cam and to said cam-follower.

12. A cartridge - case - vent-forming punching machine, including, a relatively stationary hollow magazine into which the cartridge cases to be punched are fed and in which the cartridge cases are held during the operation of the machine, a plunger slidable into and out of said magazine so as normally to enter the open end of a cartridge case or to engage the head end of a cartridge case and push a portion of the cartridge case out of the machine if the cartridge case has entered the magazine in reversed position, a power-driven mechanism connected to said plunger thereby giving sliding movement to said plunger, a clutch connecting and disconnecting said power-driven mechanism and said plunger, and a clutch-operating linkage having a part positioned so as to be engaged by the protruding portion of the cartridge case and to be operated thereby to release said clutch.

13. A cartridge-case-vent-forming punching machine, including, a relatively stationary hollow magazine into which the cartridge cases to be punched are fed and in which the cartridge cases are held during the operation of the machine, a stem mounted for sliding movement into and out of said magazine so as normally to enter a vent punched in a head of a cartridge case, power-driven mechanism connected to said stem thereby giving sliding movement to said stem, a clutch connecting and disconnecting said power-

driven mechanism and said stem, and a clutch-operating linkage having a part connected to said stem so that, when said stem engages the unvented head of a cartridge case, said stem moves said linkage to disengage said clutch.

14. A vent-hole-forming machine, including, a magazine for receiving cartridge cases or like work pieces and having a cavity extending vertically therethrough of suitable size to engage the sides of a plurality of cartridge cases, a striker movable successively to engage each of a plurality of cartridge cases and to feed each said cartridge case to the top of said cavity, feed mechanism movable toward and away from said cavity so as to feed a stack of cartridge cases through said cavity step by step, an ejector synchronized with said feed mechanism and movable to engage the bottom one of said stacked cartridge cases in said cavity and to eject it from said machine, and power-driven mechanism connected to said striker and to said feed mechanism and to said ejector so as to move them.

15. A venting machine for cartridge cases, including, a clutch controlling the connection and disconnection between the machine and a source of power, a feed mechanism for supplying a succession of cartridge cases to the machine, a position-testing mechanism movable to enter the open end of each of said cartridge cases in succession if the cartridge case is in proper position to be vented or to engage the cartridge case if it is not in proper position to be vented and to move the cartridge case and thereby operate said clutch to disconnecting position, a cooperating punch and die mounted for reciprocating movement towards and away from each other so as to receive in succession the head of each of the cartridge cases between the punch and the die whereby the die supports each cartridge case during the punching operation of the punch, and a vent-hole-testing mechanism movable to enter in succession the newly-formed correctly-located properly-sized vent hole in the head of each of said cartridge cases or to engage the improperly-punched head of the cartridge case and to be moved thereby to operate said clutch to disconnecting position.

16. A venting machine for cartridge cases, including, a clutch controlling the connection and disconnection between the machine and a source of power, a feed mechanism for supplying a succession of cartridge cases to the machine, a cam forming part of the operating-connection between said feed mechanism and the driven side of said clutch, a movable detent normally holding said cam in operative position but arranged to release said cam from operative position if said feed mechanism fails to operate properly, a position-testing mechanism movable to enter the open end of each of said cartridge cases in succession if the cartridge case is in proper position to be vented or to engage the cartridge case if it is not in proper position to be vented and to move the cartridge case and thereby operate said clutch to disconnecting position, a cooperating punch and die mounted for reciprocating movement towards and away from each other so as to receive in succession the head of each of the cartridge cases between the punch and the die whereby the die supports each cartridge case during the punching operation of the punch, and a vent-hole-testing mechanism movable to enter in succession the newly-formed correctly-located properly-sized vent hole in the head of each of said cartridge cases or to engage the improperly-punched head of the cartridge case and to be moved thereby to operate said clutch to disconnecting position.

EDWARD MOYER.
